UNITED STATES PATENT OFFICE.

GRAHAM KEARNEY, OF LISBON, OHIO.

TEE FOR GOLF BALLS.

Application filed August 26, 1926. Serial No. 131,761.

This invention relates to a tee for golf balls and more particularly to a device of this character having a peg portion which may be inserted in the ground and a pivoted tee seat connected with this portion and movable about the pivot thereof from a position where it is horizontally disposed to a vertical position in which it receives the golf ball.

10 An important object of the invention is to produce a device of this character which may be readily and cheaply manufactured and which is capable of manufacture in a variety of forms, so that a selection is provided to suit the taste of the individual users.

15 A further object of the invention is to provide a device of this character wherein the peg includes means for limiting movement thereof into the ground when the upper surface of the peg is substantially level with the ground.

20 These and other objects I attain by the construction shown in the accompanying drawings, wherein for the purpose of illustration is shown a preferred embodiment of my invention and wherein:—

25 Figures 1 and 2 are elevations particularly in section of one form of my improved tee.

30 Figures 3 and 4 are elevations partly in section of another form of tee.

Figure 5 illustrates a modified form of tee.

35 Figure 6 is an elevation of another modified form of tee.

Figure 7 is an elevation partly in section of a further modification.

40 Figure 8 is a section on the line 8—8 of Figure 7.

Figure 9 is a front elevation of a modified form of tee.

Figure 10 is an end elevation of the structure shown in Figure 9.

45 Figure 11 is a top plan view of a multiple tee having rotating arms.

Figure 12 is an elevation partly in section of the same.

50 Figure 13 is a side elevation of one of the individual tees and

Figure 14 is a top plan view of the pointer.

Referring now more particularly to the drawings, the tee in each instance includes 55 a peg 10 for insertion in the ground and a tee seat 11 having connections with the peg

10, such that the tee seat may be arranged upon the upper end of the peg 10 or may occupy a position at right angles thereto. The upper end of the tee seat is provided 60 with a socket or cup 12 upon which the ball is actually seated.

In the form of the invention disclosed in Figures 1 and 2, the peg 10 is formed with a head 13 which serves to limit its movement into the ground and this head is provided at the sides thereof with ears 14 perforated for the passage of a pin 15 upon which, intermediate the ears, the lower end 65 or base 16 of the tee seat is mounted. The 70 lower face 17 of the base of the tee seat is provided with a flattened surface which is adapted to engage the flattened upper face of the head 13 when the tee seat is perpendicularly disposed.

In the form shown in Figures 3 and 4, a similar construction is employed with the exception of the fact that the ears are produced by forming in the upper end of the peg a recess 18 and the pivot pin 19 instead of passing through the base of the tee seat passes through an eye 20 formed on the under surface 17 of the base. In the form shown in Figure 5, the 75 peg 10 has its head formed by an angular flange 22 projecting to one side of the peg and the connection between the peg and tee seat is in the form of an ordinary hinge 23 connected to the opposite face of the peg and to the corresponding face of the base 16 of the tee seat. In Figure 6, the connection 80 between the peg 10 and the tee seat 11 is in the form of a link 24 which is preferably flexible and has its ends engaged with eyes 25 and 26 carried by the peg and tee seat respectively. In the form shown in 85 Figure 7, the peg 10 at its upper end is formed as the socket 27 of a ball and socket joint and the base of the tee seat is formed as the ball 28 of this joint. In each of these constructions, the connection between the peg and the tee seat is such that the tee seat may move in the line of flight of the ball and such that movement of the tee seat without its pivot is limited when the tee seat is perpendicularly disposed.

If desired, a plurality of tee seats of different heights may be combined in a single structure. As illustrated in Figure 9, the peg 10 is made of considerable width and the head is provided with means for hinging the tee seats 11 thereto. As will be obvious by comparing Figures 1 and 3, 3

and 5, and 6 and 7, any of the connections employed in the forms heretofore described can be employed with this form of the device. By making the tee seat 11 of different heights, a tee seat of the proper height for any player may be provided. In placing the pegs in the ground, a slight depression is preferably formed in the ground in advance of the peg into which the tee seat may move when the ball is knocked therefrom. Where a plurality of the tee seats are carried by the peg, those seats not in use may be arranged within these depressions, so that they will not in any way interfere with or distract the player.

It will be noted that in some instances, it is necessary that the peg be formed in a plurality of sections, as indicated at 10^a, in Figures 11 and 13. In the form shown in Figure 12, a head 29 is rotatable upon a reduced extension 30 formed upon the upper end of the peg. Radiating from the head are a plurality of arms 31, the outer ends of which are reduced to form pintles 32 upon which tees 33 are mounted for rocking movement. Each tee seat has a weighted extension at its lower end, as indicated at 34, which is adapted to contact with the ground and limit movement of the seat when it is in a vertical position. This weighted extension has upon its under surface a shoe 35 formed of spring material and having its forward end upturned, as at 36. This spring shoe will yield to permit the tee seat to move in response to the blow imparted thereto in passage of the club head, but will restore the tee to its vertical position and will prevent the same from digging into the ground to prevent rotation of the head 29 about the extension 30.

Upon the extension 30 is mounted a small pointer 37 held in position by a set-screw 38. This pointer will be of material assistance to golfers who have a tendency to either cut or slice when driving, as the pointer can be directed toward the proper direction in which to drive the ball and the golfer in positioning the tee can so place it that he will drive to one side or the other of the line, depending upon whether he cuts or slices when he drives. It will, of course, be understood that the arms 31 will bear the tees 33 of different heights, so that a tee suiting the needs of any golfer may be provided.

Since the constructions hereinbefore set forth are obviously capable of a certain range of change and modification without materially departing from the spirit of the invention, I do not limit myself to such specific structure except as hereinafter claimed.

I claim:

65. 1. A tee comprising a peg adapted to be

forced into the ground and having a head adapted to be arranged substantially flush with the surface of the ground and a plurality of tee seats of different heights hinged to said head.

70

2. A tee comprising a peg adapted to be forced into the ground and having a head adapted to be arranged substantially flush with the surface of the ground and a plurality of tee seats of different heights hinged to said head, said head being rotatable and having radiating arms at the ends of which the tee seats are pivoted.

75

3. A tee comprising a peg adapted to be forced into the ground and having a head adapted to be arranged substantially flush with the surface of the ground, a plurality of tee seats of different heights hinged to said head, said head being rotatable and having radiating arms at the ends of which the tee seats are pivoted and a pointer carried by the peg and held against rotation with relation thereto.

80

4. A tee comprising a peg adapted to be forced into the ground and having a head adapted to be arranged substantially flush with the surface of the ground and a plurality of tee seats of different heights hinged to said head, said head being rotatable to present the desired tee seat to the user.

85

5. A tee comprising a peg adapted to be forced into the ground and having a head adapted to be arranged substantially flush with the surface of the ground and a plurality of tee seats of different heights hinged to said head, said head being rotatable and having radiating arms at the ends of which the tee seats are pivoted and an objective indicating pointer secured to said peg.

90

6. A tee comprising a peg adapted to be forced into the ground and having a head adapted to be arranged substantially flush with the surface of the ground, a plurality of tee seats of different heights hinged to said head, said head being rotatable and having radiating arms at the ends of which the tee seats are pivoted and a pointer carried by the peg and held against rotation with relation thereto and an objective indicating pointer secured to said peg.

95

7. A tee comprising a peg adapted to be forced into the ground and having a head adapted to be arranged substantially flush with the surface of the ground, a plurality of tee seats of different heights hinged to said head, said head being rotatable and having radiating arms at the ends of which the tee seats are pivoted, a pointer carried by the peg and held against rotation with relation thereto and a spring shoe secured to each of said tee seats at the bottom thereof and projecting therefrom in the general direction of movement of the arm to which the tee

100

110

115

120

125

130

seat is attached when a ball is struck from the tee.

8. A tee comprising a peg adapted to be forced into the ground and having a head adapted to be arranged substantially flush with the surface of the ground, a plurality of tee seats of different heights hinged to said head, said head being rotatable and having radiating arms at the ends of which 10 the tee seats are pivoted, a pointer carried by the peg and held against rotation with

relation thereto and a spring shoe secured to each of said tee seats at the bottom thereof and projecting therefrom in the general direction of movement of the arm to which the tee seat is attached when a ball is struck from the tee, said tee having engagement with the ground limiting its movement to a vertical position. 15

In testimony whereof I hereunto affix my 20 signature.

GRAHAM KEARNEY.
